CLAIM

We claim the ornamental design for a crankcase ventilation device housing, as shown and described.

DESCRIPTION

FIG. 1 shows a left front perspective view of a crankcase ventilation device housing showing our new design;
FIG. 2 shows a left side elevational view thereof;
FIG. 3 shows a right side elevational view thereof;
FIG. 4 shows a front elevational view thereof;
FIG. 5 shows a rear elevational view thereof;
FIG. 6 shows a top plan view thereof; and,
FIG. 7 shows a bottom plan view thereof.
The broken lines illustrate the portions of the crankcase ventilation device housing that forms no part of the claimed design.
